UNITED STATES PATENT OFFICE.

GEORGE F. RIDER, OF CHICAGO, ILLINOIS.

DESIGN FOR A MEDAL OR SIMILAR ARTICLE.

Application filed March 23, 1929. Serial No. 30,598. Term of patent 14 years.

To all whom it may concern:

Be it known that I, GEORGE F. RIDER, a citizen of the United States, residing at Chicago, in the county of Cook and State of Illinois, have invented a new, original, and ornamental Design for Medal or Similar Article, of which the following is a specification, reference being had to the accompanying drawings forming a part thereof.

In the drawings Fig. 1 is a face view of one side of a medal, showing my design, Fig. 2 a similar view of the reverse side, and Fig. 3 an edge view of the same.

I claim:

The ornamental design for a medal or similar article as shown.

GEORGE F. RIDER.
